UNITED STATES PATENT OFFICE.

SEELEY P. MOUNT, OF CLEVELAND, OHIO.

METHOD OF ATTACHING ADVERTISING ARTICLES TO CARDS.

SPECIFICATION forming part of Letters Patent No. 295,665, dated March 25, 1884.

Application filed June 27, 1883. (No model.)

To all whom it may concern:

Be it known that I, SEELEY P. MOUNT, of Cleveland, in the county of Cuyahoga and State of Ohio, have invented a certain new and useful Improvement in Advertising-Cards, of which the following is a specification.

This invention relates to a method of attaching a miniature article of wearing-apparel or other article of manufacture to a business-card, as will be hereinafter described, and particularly pointed out in the claim.

In the accompanying drawings, Figure 1 is a face view of a business-card, showing a miniature article attached; and Fig. 2 is vertical sections of the same on line $x x$, Fig. 1.

The letter A represents a business-card having near its edge a slot, C, and above said slot a strip, a.

B represents the miniature article, made of any suitable material, and consists of two portions connected together by a narrow piece, b.

The letter D denotes the ring for securing the parts together.

The manner of attaching the article to the card is as follows: Fold the card A at its central or middle portion; then slip the ring on the folded strip a; adjust one of the portions of the article between the folded portions of the strip, so that the connecting-piece b will rest upon the upper edge thereof; then move the ring forward off from the folded strip and release it therefrom, so that when the card is straightened out the ring will rest in the slot of the card over the folded connecting-piece

30 and encircle them, whereby one portion of the article will be suspended in front and the other on the back of said card. To detach

the article from the card, fold said card at its middle portion; then bring the ring D over the connecting-piece b and back onto the folded strip a, and then draw the rear portion of the article through said folded strip, thereby releasing said article from the card, and finally slipping the ring off from the folded strip. The combination of said card and article as an advertising medium gives additional value and interest to the same, and at the same time is rendered more attractive and amusing by means of its being a puzzle to attach and detach the miniature.

Having described my invention and the operation thereof, what I claim is—

The method of attaching a miniature advertising article, consisting of two portions connected by a narrow piece, b, to a card, A, having a slot, C, near its edge, forming a strip, a, consisting, first, in folding the card at its central portion; second, in sliding a ring onto the folded strip; third, in passing a part of the divided article between the folded portions of the strip, so that the connecting-piece will rest upon the upper edge of the strip, and, fourth, in moving the ring back off from the folded strip and releasing it, so that when the card is straightened out the ring will rest in the slot over the folded connecting-piece b, and one portion of the advertising article will be suspended in front and the other on the back of the card, as set forth.
